UNITED STATES PATENT OFFICE

JOSEPH BEHLE, OF DALLAS, TEXAS, ASSIGNOR TO THE MURRAY COMPANY, OF DALLAS, TEXAS, A CORPORATION OF TEXAS

GIN RIB GRINDING MACHINE

Application filed June 29, 1929. Serial No. 374,756.

This invention relates to a grinding machine, and particularly to a construction adapted to grind or finish a gin saw rib and embodying a carrier mounted to reciprocate beneath a grinding wheel and supporting the work and a form to guide said wheel.

In such grinding of an irregular or curved object it has been found important to properly adjust the elevation of the grinding wheel relative to the work so that when guided in its travel by a form moving with the work carrier the proper depth of cut will be secured to effect an accurate finish of the ribs which are fitted between the gin saws. In order to prevent grooving of the grinding wheel when operating on a narrow object of this character the work is given a continuous transverse movement across its longitudinal path of travel beneath the wheel and the result of these two movements of the carrier is an even wearing of the wheel and complete grinding of the surface of the work.

The invention has for an object to provide a novel and improved construction of grinding machine including a grinding wheel yieldingly mounted and carrying on its shaft a guide roller, and a work carrier mounted for longitudinal movement beneath the wheel and for movement axially thereof.

20 A further object of the invention is to present a new structure of rib grinding machine in which the grinding wheel is mounted in a pivoted yoke and carries on its shaft a tapering guide roller and drive pulley, together with a work carrier aligned with the grinding wheel, a guide form cooperating with the roller and adjustable axially thereof, and means for reciprocating said carrier and form.

40 A further object of the invention is to provide an improved carrier mechanism consisting of a work holder and guide form mounted for axial movement upon a carriage travelling on the machine frame, a grinding wheel and guide roller cooperating with said holder and form, a shift bar provided with adjusting means and engaging the guide form, and a shift bar engaging the work holder and provided with driven means to oscillate the bars transversely to its length.

Other and further objects and advantages of the invention will be hereinafter set forth and the novel features thereof defined by the appended claims.

Figure 1 is a front elevation of the machine,

Figure 2 is a side elevation thereof from the left,

Figure 3 is a top plan,

Figure 4 is an enlarged vertical section of the carrier driving means,

Figure 5 is an elevation of the work grip at one end of the holder,

Figure 6 is a plan thereof,

Figure 7 is a plan of the grip at the opposite end of the work holder,

Figure 8 is a side elevation thereof,

Figure 9 is an elevation of the control means for the shift bar of the work holder,

Figure 10 is a section on line 10-10 of Figure 9,

Figure 11 is a horizontal section of the reversing drive means,

Figure 12 is a vertical section of the same,

Figure 13 is a detail vertical section of the guide form adjusting means,

Figure 14 is a section on line 14-14 of Figure 13,

Figure 15 is a section on line 15-15 of Figure 14,

Figure 16 is a detail section of the carrier drive means, and

Figures 17 and 18 are details of the work holder control means.

Like numerals of reference indicate like parts in the several figures of the drawings.

In the preferred form of the invention as herein disclosed the numeral 10 designates a base upon which opposite side standards 11 are supported and connected by a brace bar

12. Intermediate these standards are a series of cross beams 13 forming supports for parts of the mechanism.

The rib holder or carrier 14 is provided with work grips 15 and 16 at its opposite ends and is mounted upon a carriage base 17 extending between the axles 18 upon which it is mounted by bearings 19. The axles are provided with rollers 20 which traverse the track bars 21 mounted upon the standards

85

90

95

100

11, and the front and rear axles are connected by rods 22 and bearing brackets 23 on the axles. The driving rack 24 is supported from these axles by the bearings 25, and meshes 5 with a gear 26 secured to the countershaft 27 carried by bearings 28 depending from the track bars 21. The countershaft 27 also has secured thereto a pinion 29 meshing with a gear 30 upon the drive shaft 31 supported 10 by bearings 32 on the standards 11.

The shaft 31 is provided with a wheel or pulley 33 adapted to be driven alternately in opposite directions by tangential contact with the smaller wheels 34 and 35, all of said 15 wheels being faced with suitable material to prevent slippage. The wheels 34 and 35 are carried by shafts 36 and 37, respectively, and these shafts are mounted in a lever bearing 38 supported by a control shaft 39 operating in bearing 40 upon the standards 11, see Figure 11. The control shaft is actuated by a manually operated lever 41 extending to the end of the frame and there guided by a slotted hanger 41a provided at its lower 25 end with a casing 41b for a supporting spring 41c disposed beneath the lever. The drive shafts 36 and 37 are provided with fast pulleys 43 and 44 respectively, from which suitable drive belts 43a and 44a extend to a 30 source of power (not shown). The belt 44a from pulley 44 is reversed so as to impart rotation in opposite directions to the wheels 34 and 35.

The carrier 14 is grooved longitudinally 35 at 14a to receive the base of the cotton gin rib A to be ground, and this rib is held in position at one end by a grip 16 overlapping the foot C of the rib and held under tension of the springs 16a at opposite sides, as shown 40 in Figures 5 and 6. The foot B at the opposite end of the rib is held upon the work holder by the clamp 15, which, as seen in Figures 7 and 8, comprises the jaws 47 actuated laterally of the holder by the screw 47a. 45 Intermediate of the groove 14a a brace 45 is disposed in notches 46 to engage and support the under face of the rib A.

A master rib form 48 is located parallel to the carrier 14 and has its upper surface 48a conforming to the curvature of the rib to be ground. This form is adapted to be traversed by the tapering guide roller 49 mounted on a shaft 50 carried by bearings 50a supported by a yoke 50b with bearings 50c upon the standards 11 at their rear. The yoke is formed with a brace 50d about which a cable 55 is looped and attached to a counterbalance (not shown). Brackets 56 are also secured to the yoke to hold the roller 49 in position, and an operating arm 56a is extended longitudinally from the yoke and provided with a depending handle portion 56b, as shown in Figure 2. By means of this arm and the counterweight the grinding wheel 73 may be raised or lowered relative to the work. The

shaft 50 is driven by a fast pulley 51 thereon from which a belt 52 extends to a pulley 53 on the armature shaft of the electric motor 54 supported upon the rear beam 13. The grinding wheel 73 is formed of carborundum or other suitable material and secured to the shaft 50 in alignment with the carrier 14 for the rib.

In Figures 13, 14 and 15 means are shown for shifting the guide form 48 lengthwise of the roller 49 and these comprise the screw 57 carrying the adjusting wheel 58 and locking wheel 59. This screw is connected by a ball and socket joint 60 to a rod 61 connected by a similar socket 62 to a lever 63 secured to a shaft 64 which also carries a crank lever 65 retained by a brace 66. The shaft 64 passes upward through a bearing 68 on a front beam 13 and carries at its top a lever 69 pivoted to the shift bar 70 which extends longitudinally of the frame and is supported at its opposite ends by the sleeves 84 upon the shafts 85.

A longitudinal rod 71 is connected to the lever 65 by a universal joint 67 and extends to a similar lever 65a at the rear of the machine which also actuates a shaft 65a in a bearing 68a and carrying the lever 69a connected to the rear end 70a of the shift bar 70. The screw 57 when operated inward to the dotted line position Y in Figure 13 shifts the form as there shown and causes it to move upward on the roller 49, if in contact, thus raising the shaft and the grinding wheel which permits of its adjustment as the wheel becomes worn.

The work holder 14 is also longitudinally adjustable upon its supports 18 by a shift bar 70b similar to the bar 70 and supported at its front and rear by sleeves 84a on the shafts 85 before described. The bar 70b is actuated by a lever 86 mounted on a shaft 87 carried in bearing 88. At the opposite end of the shaft 87 is mounted a lever 89 connected to a rod 71a by a joint 90. The rear of the rod 71a is connected to the lever 74, by a joint 90a mounted on a shaft 87a carried in a bearing 88a. At the opposite end of the shaft 87a is mounted a lever 86a which actuates the rear of the bar 70b. The rear of rod 71a from lever 89 is connected to a double lever 74 by a socket 90a and from the opposite end of this lever a rod 82 extends to a socket 75 eccentrically mounted upon a wheel 76 upon a shaft 77 supported in bearings 78 on one standard 11. This shaft is driven by a chain 80 extending over a sprocket 79 thereon and over a sprocket 81 secured to shaft 27 by which the carrier and form are reciprocated. See Figures 9 and 10. This longitudinal movement of the work holder constantly shifts the rib laterally of the face of the grinding wheel and prevents the formation of channels or grooves therein and undue wear at any portion.

In the operation of the invention a depression of the lever 41 raises the shaft 37 to bring the drive wheel 35 against the pulley 33 on shaft 31 which, through the gears 5 30, 29 and 26 actuate the drive bar 24 for the carriage supporting the work holder and form. The shaft 27 transmits motion to the sprocket 81 which through the chain rotates shaft 77 and wheel 76. The eccentric connection to this wheel causes rod 82 to reciprocate and oscillates the double lever 74 which through the connecting rod 71a shifts the bar 70b to cause a lateral movement of the rib holder and the surface being ground 10 to continuously traverse the face of the grinding wheel. In the movement to the left from the position of parts shown in Figure 4, the roller rides upon the form and thus guides the grinding wheel in the accurate 15 path or contour to be ground upon the work which is subjected to longitudinal and transverse movements during such grinding. The detail operation of the several parts of the machine will be obvious from the foregoing description.

The invention has been described as particularly designed for grinding the outer face of cotton gin ribs, still it is applicable to other grinding work by changing the configuration of the work holder and guide form to correspond with the work to be ground. While the details of the invention have been shown and described it is not confined thereto as changes and alterations may 20 be made therein without departing from the spirit of the invention as recited in the following claims.

What I claim, is:

1. In a grinding machine, a shaft provided with a grinding wheel, a work carrier, means for reciprocating the carrier under the wheel longitudinally, means for reciprocating the carrier transversely during the longitudinal movement, a guide form movable with 40 said carrier, a roller upon said shaft disposed to traverse said form, a manually operated adjuster for shifting said form axially of the roller, a common drive shaft for the carrier and form, and a connection from said drive shaft for continuously reciprocating the carrier axially of the grinding wheel.

2. In a grinding machine, a shaft provided with a grinding wheel and a guide roller, a carriage provided with a work holder and form alined with said roller, means for reciprocating said carriage beneath the wheel, and means for shifting said form axially of the roller to elevate the grinding wheel.

3. In a grinding machine, a yoke pivoted at one end of the machine frame, a grinding wheel, tapering roller and driving pulley carried by a shaft in said yoke, a drive shaft at the pivot of the yoke having a connection with said pulley, a carriage provided with a work holder alined with said wheel and a

form alined with said roller, and means for reciprocating said carriage.

4. In a grinding machine, a yoke pivoted at one end of the machine frame, a grinding wheel, tapering roller and driving pulley carried by a shaft in said yoke, a drive shaft at the pivot of the yoke having a connection with said pulley, a carriage provided with a work holder alined with said wheel and a form alined with said roller, means for reciprocating said carriage, comprising oppositely rotated drive pulleys, an intermediate main pulley having a shaft geared to a reciprocating rack on the carriage, and means for shifting either of the drive pulleys into contact with the main pulley.

5. In a grinding machine, a yielding mounted shaft provided with a grinding wheel and guide roller, a carriage supported upon the machine frame and having parallel axles, a driving rack upon said carriage, means for actuating said rack, a work holder slidingly mounted upon said axles, a guide form slidingly mounted upon said axles, longitudinal shift bars for said holder and form engaging projections therefrom, manually operated levers for adjusting the shift bar for the form, and a driving connection for continuously actuating the shift bar for the holder.

6. In a grinding machine, a yielding mounted shaft provided with a grinding wheel and guide roller, a carriage supported upon the machine frame and having parallel axles, a driving rack upon said carriage, means for actuating said rack, a work holder slidingly mounted upon said axles, a guide form slidingly mounted upon said axles, longitudinal shift bars for said holder and form engaging projections therefrom, manually operated levers for adjusting the shift bar for the form, a shaft from the rack actuating means provided with a sprocket, a chain connection therefrom to a sprocket on a countershaft, an eccentric connection upon the countershaft, a rod extending from the eccentric, and a leverage system actuated by said rod for imparting a horizontal oscillation to the shift bar for the work holder.

7. In a grinding machine, side standards having trackways upon their upper surface, beams connecting the front and rear of said standards, a swinging yoke pivoted upon the rear beam, a shaft at forward portion of said yoke carrying a grinding wheel, a guide roller and a driving pulley, means from the pivot of the yoke for driving said pulley, a carriage mounted on said trackways, a work holder upon the carriage and alined with said wheel, a form upon the carriage to co-operate with said roller, a shaft connected to reciprocate said carriage, a driving pulley on said shaft, oppositely driven wheels disposed to engage the periphery of said driving pulley, a rock lever carrying on its

opposite ends the said opposite driven wheels, and means for oscillating said rock lever to alternately engage said wheels with the pulley.

- 5 8. In a grinding machine, side standards having trackways upon their upper surface, beams connecting the front and rear of said standards, a swinging yoke pivoted upon the rear beam, a shaft at forward portion of 10 said yoke carrying a grinding wheel, a guide roller and a driving pulley, means from the pivot of the yoke for driving said pulley, a carriage mounted on said trackways, a work holder upon the carriage and aligned with 15 said wheel, a form upon the carriage to cooperate with said roller, a shaft connected to reciprocate said carriage, a driving pulley on said shaft, oppositely driven wheels disposed to engage the periphery of said driving pulley, a rock lever carrying on its opposite ends the said opposite driven wheels, means for oscillating said rock lever to alternately engage said wheels with the pulley, shift bars slidably mounted at the opposite 20 ends of the said standards and engaging said work holder and form to reciprocate transversely upon the said carriage, manually operated means for adjusting said shift bar for said form, and automatically operated 25 means for continuously reciprocating the said work holder transversely during the travel of the carriage.

9. In a grinding machine, a support, a rotatable shaft above said support, a grinding 30 wheel mounted on said shaft, a work carrier mounted to reciprocate on said support, a guide form movable longitudinally with the carrier, means for longitudinally reciprocating the carrier and the guide form, means 35 for moving the carrier transversely independently of the form during the longitudinal movement of the carrier and the guide form, means for moving the guide form transversely independently of the carrier 40 and a roller on the shaft travelling on said guide form.

10. In a grinding machine, a support, a grinding wheel rotatably mounted above the support, a guide roller having an inclined 45 surface and connected with the grinding wheel, a reciprocating work carrier mounted on the support for longitudinal movement under the wheel, a guide form mounted for longitudinal movement and engaged by the 50 inclined surface of the roller, means for moving the carrier transversely independently of the form during the longitudinal movement of the carrier and the guide form and means for adjusting the form to compensate 55 the wear of the grinding wheel.

11. In a grinding machine, a shaft provided with a grinding wheel, a roller, a vertically swinging support for the shaft, trackways beneath said shaft, a carriage mounted to 60 travel upon said trackways beneath the said

wheel, a work holder mounted to reciprocate transversely upon the carriage, a guide form on said carriage for the roller, a rack on said carriage, a gear engaging the rack for driving said carriage, and means for reciprocating transversely the work holder during the travel of the carriage.

12. In a grinding machine, a shaft provided with a grinding wheel, a vertically swinging support for the shaft, trackways beneath said shaft, a carriage mounted to travel upon said trackways beneath the said wheel, a work holder mounted to reciprocate transversely upon the carriage, a guide form on said carriage, a rack on said carriage, a gear engaging the rack for driving said carriage, a guide form laterally movable upon the carriage, a longitudinal shift bar engaging said form, manually operated means for adjusting said bar, and a tapering roller upon said shaft disposed to traverse the form.

13. In a grinding machine, a shaft provided with a grinding wheel, a roller, a vertically swinging support for the shaft, trackways beneath said shaft, a carriage mounted to travel upon said trackways beneath the said wheel, a work holder mounted to reciprocate transversely upon the carriage, a guide form on said carriage for the roller, a rack on said carriage, a gear engaging the rack for driving said carriage, means for reciprocating transversely the work holder during the travel of the carriage, a master pulley for said driving means, and oppositely rotated drive pulleys mounted for alternate engagement with the periphery of said master pulley.

14. In a grinding machine, a shaft provided with a grinding wheel, a roller, a vertically swinging support for the shaft, trackways beneath said shaft, a carriage mounted to travel upon said trackways beneath the said wheel, a work holder mounted to reciprocate transversely upon the carriage, a guide form on said carriage for the roller, a rack on said carriage, a gear engaging the rack for driving said carriage, a shift bar extending longitudinally of the work holder and engaging the same, and levers connected to said bar for oscillating the same in a horizontal plane.

15. In a grinding machine, a rotatable shaft, a vertically swinging support for the shaft, a grinding wheel mounted on the shaft, a guide roller mounted on said shaft, a carriage reciprocating transversely of the shaft, a work holder on said carriage, a guide form mounted on said carriage and engaged by said roller, means for moving the work holder laterally during its reciprocation, and means for adjusting the guide form laterally independently of the work holder.

16. In a grinding machine, a work carrier mounted to shift transversely, projections depending from the said carrier, a shift bar disposed between the projections, a pair of ver-

tical shafts, an arm extending from each shaft to the shift bar, a lever extending from each shaft, a rod connected to each lever, a second rod attached to one of the levers, and 5 means for reciprocating the second rod.

17. In a grinding machine, a support, a work carrier mounted to reciprocate on said support, a grinding wheel above the carrier, a guide roller connected to the wheel and having 10 an inclined surface, a guide form mount-

ed for longitudinal movement and engaging the inclined surface of the roller, a shift bar engaging the guide form, a pair of vertical shafts, levers connecting each shaft to the ends of the bar, arms extending from the 70 shafts, a rod connected to the arms, and means for actuating one of the shafts to shift the bar to adjust the form.
